WEB SUPPLYING AND CONTROLLING MECHANISM

Original Filed March 22, 1928 3 Sheets-Sheet 3

UNITED STATES PATENT OFFICE

CHARLES J. RICHTER, OF BEBWYN, ILLINOIS, ASSIGNOR TO GOSS PRINTING PRESS COMPANY, A CORPORATION OF ILLINOIS

WEB SUPPLYING AND CONTROLLING MECHANISM

Original application filed March 22, 1928, Serial No. 263,624. Divided and this application filed July 26, 1930. Serial No. 470,820.

The invention relates to novel and useful improvements in web pasting means for webs drawn from rotatable rolls, and in certain aspects thereof the invention relates more particularly to such means as applied to fast rotary printing press, although in other of its features the invention has other applications.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

20 This application is a division of my prior application Ser. No. 263,624, filed March 22, 1928.

The accompanying drawings, referred to herein and constituting a part hereof, illustrate one embodiment of the invention and together with the description, serve to explain the principles of the invention.

Of the drawings:—

Fig. 1 is a side elevation of a mechanism embodying the invention;

Fig. 2 is an enlarged, fragmentary, end elevation, taken substantially on line 2—2 of Fig. 1;

Fig. 3 is a positional diagram showing the operation of pasting the webs; and

Figs. 4 and 5 are fragmentary elevations showing different stages in the pasting of the webs.

Referring now in detail to the embodiment of the invention illustrated by way of example in the accompanying drawings, the invention is shown applied to a type of web-supplying means for printing presses, wherein two web supply rolls are contiguously mounted on the machine frame, an exhausted roll being removed and replaced by a fresh full roll while the web from the other roll is running to the printing machine. The present invention provides novel means for bringing a fresh web supply roll approxi-

mately up to speed and attaching the two webs together to lead the fresh web through the printing press or other machine.

Referring now in detail to the present preferred embodiment of the invention, a frame 55 1 has at either side upright frame members 2 and 2', and each of these has oppositely-projecting brackets 3 and 4, which are adapted, respectively, to support the shafts of web supply rolls *a* and *b* in operative relation to the tension controlling means and the web pasting mechanism. Two brake mechanisms are provided, one cooperating with web supply roll *a* and the other cooperating with web supply roll *b*, both brake 60 mechanisms being governed by a common control to the web-tension governed controlling means. The brake mechanisms are preferably constructed and arranged so that an exhausted roll may be removed and a new 70 web supply roll may be inserted without displacing the brake mechanisms from their mounting on the machine, or disconnecting them from the common control. A single description is sufficient for both mechanisms. 75

The roll mounting and brake mechanisms may comprise a shaft or mandrel 10 passing through the web supply roll in the usual manner, the mandrel being journaled in the side brackets 3, 3 or 4, 4 of the frames. A 80 new web supply roll is rolled in from the exterior end of the brackets along the tops thereof to the bearings for its shaft 10. A brake pulley 15 is fixed in position on one end of shaft 10 which projects outside of the 85 corresponding bearing in frame bracket 3, the brake pulley being provided with a peripheral V-shaped groove. Working in the groove in the pulley are two arcuate V-shaped brake shoes 16 and 17, which are pivoted to the ends of opposed pairs of brake arms 20 and 21. The web tension controlling mechanism for the web rolls may be of any desired or convenient type but is preferably of the type shown and claimed in the 90 parent application Ser. No. 263,624, and is so shown in the accompanying drawings. Inasmuch as this part of the mechanism forms no part of the present invention, a detailed 95 description of this mechanism is not included. 100

Referring now in detail to the embodied form of web pasting means, there is provided a pair of bracket plates 161 and 162 fixed on the machine frame at either side. At one end of each of the plates 161 and 162 is formed a slot guideway 163, and at the opposite end of each of the plates 161 and 162 is formed a corresponding slot guideway 164, these guideways cooperating respectively with two rollers which are used alternatively to press together a running and nearly exhausted web and the lead end of the web from the fresh supply roll to make what is known as a running paster.

In the embodied form of mounting and moving means for said web pasting rollers, there is journaled in the side frames 2 and 2' of the machine a shaft 171, and fixed thereon are two arms 172 and 173. Pivottally supported in the top of the arm 172 is a bar 174, and pivotally supported in the top of the arm 173 is a bar 175. A roller 179 has its shaft journaled in the corresponding ends of the bars 174 and 175. To hold the roller 179 in longitudinal position and the bars 174 and 175 in alinement and position, the ends of the roller axle are shouldered within the bars (Fig. 2). The shaft 182 of the roller 179 at either end of the roller and within the respective bars 174 and 175 is adapted to pass into and out of the slot guideways 163 formed in the plates 161 and 162 fixed on the machine frame. In the opposite ends of the bars 174 and 175 is journaled a roller 185 which together with roller 179, may be provided with a resilient covering, as of rubber, the roller shaft 187 being held in place against longitudinal displacement, and the corresponding ends of the bars 174 and 175 being held in alinement and position by similar means to those already described in connection with roller 179. The shaft 187, at either end of the roller 185 and within plates 161 and 162 is adapted to enter into and travel along the slot guideways 164 in the plates, similarly to the mechanism and operation at the other side of the press. Means are provided for manually rocking shaft 171 to effect the pasting operation at either side. Said means as embodied comprises a lever 191, fixed to one end of shaft 171 on the outside of the side frame 2 of the machine. A boss 192 on the lever cooperates with a boss 193 on the frame when the mechanism is in central or inactive position, as shown in Figs. 1 and 2, and a pin 194 passes into internal apertures in the two bosses and holds the lever 191 locked in inactive position. The entire mechanism is rocked either to the right or left about shaft 171, and one of the rollers 179 or 185 is guided by the corresponding pair of slots 163 or 164, moving to and fro in the slots during the rocking of the entire device about shaft 179 to simultaneously swing the rollers 174 and 175 about their pivotal mounting on

arms 172 and 173 to move the other roller to and from pasting position. This action will be apparent from Figs. 1, 3, 4 and 5. In the diagram of Fig. 3 it is assumed that the web *b*, approaching exhaustion, is to be pasted to a fresh web roll *a*. Handle 191 is turned to the left, and the successive positions of the various parts of the mechanism are indicated by exponents *a*, *b* and *c* applied to the reference numerals for those parts. In practice, the lead end of the web of roll *a* has a band of paste applied thereacross and it is located just beyond the point where roll 179 will contact therewith. When roll 179 is impressed in position 179*c*, it presses the running web *b* firmly against roll *a* which is thereby started into rotation, or roll *a* may be otherwise started to rotate. It has practically an entire revolution in which it is brought up to speed by the pressure of running web *b* under roller 179*c*. As the band of paste on rotating roll *a* engages with running web *b*, they are pasted together, web *b* is severed, and the lead of web *a* is carried through the printing press or other machine.

The invention in its broader aspects is not limited to the specific mechanisms shown and described but departures may be made therefrom within the scope of the accompanying claims without departing from the principles 95 of the invention and without sacrificing its chief advantages.

What I claim is:—

1. A web attaching mechanism including in combination means for rotatively supporting a plurality of web rolls, a roller journaled at either side of a running web, a movable support for both said rollers, a movable support for said movable support and additional means for guiding one of said rollers out of contact with the fresh web roll. 100
2. A web attaching mechanism including in combination means for rotatively supporting a plurality of web rolls, a roller journaled at either side of a running web, a movable support for both said rollers, a movable support for said movable support, and additional means for guiding one of said rollers out of contact with the fresh web roll while the other roller is pressing a running web 115 against a fresh web roll. 110
3. A web attaching mechanism including in combination means for rotatably supporting a plurality of web rolls, a roller at either side of a running web, a frame in which said rollers are journaled, pairs of guideways in which one side of the frame is always received and means for moving the frame in said guideways to cause one of said rollers to press the running web against a fresh web 120 roll. 125

4. A web attaching mechanism including in combination means for rotatably supporting a plurality of web rolls, a roller at either side of a running web, a frame in which said 130

rollers are journaled, guideways at either side of said frame and into which said frame is movable, an oscillatable support on which said frame is pivoted, and means for moving 5 said frame to cause one of said rollers to press the running web into contact with the fresh web roll.

5. A web attaching mechanism including in combination means for rotatably supporting a plurality of web rolls, a roller at either side of a running web, a frame in which said rollers are journaled, divergent guideways extending away from said web rolls at either 10 side of the frame and into which said frame is movable, a pivoted support connected with said frame, and means for moving said frame to cause it to enter one or the other of said guideways whereby one of said rollers is caused to press the running web into contact 15 with a fresh web roll.

6. A web attaching mechanism including in combination means for rotatably supporting a plurality of web rolls, a roller at either side of a running web, a frame in which said 20 rollers are journaled, guides in which said frame is always movable, said guides being shaped to provide divergent paths for the guided end of the frame whereby one of the rollers is caused to press the running web 25 against the fresh web roll while the other roller is held out of engagement with the running web.

In testimony whereof, I have signed my name to this specification.

35 CHARLES J. RICHTER.
